FIG. 5

UNITED STATES PATENT OFFICE

ALLAN A. AITKEN, OF MONTREAL, QUEBEC, CANADA

HUMIDIFIER

Application filed November 21, 1929. Serial No. 408,910.

This invention relates to humidifiers of the portable hydroelectric type, in which steam is generated by immersing spaced electrodes in a body of water contained in a suitable 5 vessel.

The objects of the invention are to provide a humidifier which is compact, easy to handle and economical to manufacture; to provide a humidifier in which relatively small 10 quantities of water are substantially segregated from a surrounding main body of water and rapidly converted into steam; to provide a humidifier in which the said relatively small quantities of water are segregated within 15 in a non-conducting, heat insulating, steam generating vessel surrounded by the main body of water contained in a suitable outer vessel which is also made of non-conducting material; to provide a humidifier in which 20 steam is generated in said steam generating chamber without substantially raising the temperature of the surrounding body of water; to provide a humidifier which may be handled with absolute safety while in operation; to provide a humidifier equipped with 25 electrodes having the lower portions enlarged to compensate for the lowering of the water level during the progress of steam generation; to provide a humidifier equipped with 30 electrodes shaped to prevent excessive current discharge between the edge portions thereof; and, finally, to provide a humidifier in which the electrodes and the current charged water are rendered inaccessible while 35 the humidifier is in operation, thereby eliminating the danger of accidental shock or electrocution.

Other objects and advantages of the invention will be more readily understood from the following detailed description taken in connection with the accompanying drawings.

In the drawings,

Figure 1 is a side elevation of a humidifier constructed in accordance with my invention.

Figure 2 is a transverse sectional view.

Figure 3 is a fragmentary transverse sectional view taken along the line 3—3 Figure 2.

Figure 4 is a transverse sectional view 50 taken along the line 4—4 Figure 2.

Figure 5 is a perspective view of a particular form of clamp.

Referring more particularly to the drawings, 11 designates a bowl shaped container made of glass or other suitable insulating material. The upper portion of the container is inwardly curved, as indicated at 12, and terminates in an outwardly flanged rim 13 surrounding a filling opening 14. The filling opening is closed by a cover 15 which is 55 preferably made of a suitable non-conducting heat insulating material such as porcelain. The marginal portion of the cover is shaped to snugly engage a seat 16 formed around the inner edge of rim 13. The central portion 60 of the cover is made in the form of a hollow steam dome 17 provided at the top with a relatively small central opening 18.

The cover 15 carries a pair of opposing electrodes 19 and 20 having their opposing 70 body portions spaced apart by an interposed disk 21 formed of suitable insulating material and provided with supporting trunnions 22 received in suitable openings formed in said electrodes. At their upper ends the electrodes 19 and 20 are provided with offset extensions 23 and 24, which lie flat against an interior wall 25 of the dome 17 and are spaced from one another by the interposition of a rib 26 (Fig. 3) formed integral with said 75 wall. Passing through the wall 25 are a pair of terminals 27 having their inner ends equipped with nuts 28 by means of which the electrode extensions 23 and 24 are clamped to said wall. The outer portions of the terminals 27 are contained in a recess 29 (Fig. 2) formed in one side of dome 17. This recess affords a receptacle for a plug 30 which is connected to any suitable source of current and is provided with suitable terminal sockets 31 80 for the reception of the terminals 27. This plug carries a hook 32, which, when the plug is applied, as shown in Figure 2, is adapted to engage beneath the outwardly flanged 85 rim 13.

Surrounding the electrodes 19 and 20 and formed integral with the cover 15 is a depending collar 33. This collar provides an abutment for the upper edge of an inner vessel or jar 34. The vessel 34 is also formed of non- 95 100

conducting heat insulating material such as porcelain and provides a housing for the electrodes 19 and 20. The joint formed by the contacting edges of the collar 33 and the inner vessel 34 is sealed by a suitable gasket 35 surrounded by a split clamp 36. This clamp, as shown to advantage in Figures 2 and 5, has its free terminals split longitudinally as indicated at 36a, in order to provide a pair of upper clamping fingers 36b, and a pair of lower clamping fingers 36c. Suitable bolts 36d are passed through the fingers of each pair and are equipped with clamping nuts 36e. When the clamp is arranged as shown in Figure 1, the upper fingers 36b are drawn tightly around the collar 33, while the lower fingers 36c are drawn tightly around the upper end of the inner vessel or jar 34.

The clamp 36 carries a laterally projecting member 39 adapted, as shown in Figures 1 and 2, to engage beneath the inwardly curved portion 12 of the container 11. This projection 39 co-operates with the hook 32 of the plug 30 to prevent removal of the cover 15 when the plug is in the applied position shown in Figures 1 and 2. In order to remove the cover, it is necessary to disconnect the plug 30 and this, of course, interrupts the flow of current to the electrodes 19 and 20 and discontinues the charging of the water in container 11. This is an important safety feature whereby access to the electrodes or to the interior of the vessel 11 is prevented while the humidifier is in operation, thus eliminating all danger of accidental shock or electrocution.

The inner jar or vessel 34 is provided with a relatively small bottom opening 42 through which a comparatively small volume of water 40 is caused to flow into the interior of said jar and is thereby substantially segregated from the main body of water contained in the container 11. The small volume of water, segregated within the jar 34, is rapidly converted 45 into steam by means of the electrodes 19 and 20 and without raising the temperature of the surrounding main body of water to the boiling point. As a matter of fact, the main body of water surrounding the inner vessel or jar 34 will remain at a temperature low 50 enough to permit the container 11 to be safely handled without danger of being burnt.

As shown to advantage in Figure 3, the electrodes 19 and 20 are made of gradually 55 increasing width towards their lower ends so as to compensate for the gradual lowering of the water level during the progress of steam generation. By employing electrodes of this particular design, it has been found 60 that the quantity of steam generated varies only slightly over a comparatively long period of operation. It will also be noted that the electrodes are cupped or transversely curved so that the edge portions of each electrode extend in a direction away from the op-

posing electrode. This construction is of advantage, in that it eliminates sharp edges which cause excessive passage of current between the marginal portions of the electrodes.

Having thus fully described what I now 70 consider to be the preferred embodiment of my invention, it will be understood that various modifications may be resorted to within the scope and spirit of the appended claims.

Having thus described my invention, what 75 I claim is:—

1. A humidifier comprising a water container, a removable cover closing a filling opening formed in said container, electric steam generating means positioned in said container and including suitable terminals carried by the cover, a plug engageable with said terminals for connecting the steam generating means to a suitable source of current, and co-operating elements carried by said 80 cover and plug for engaging the container to prevent removal of the cover when the plug is applied to said terminals.

2. A humidifier, comprising a water container, a movable cover closing a filling opening formed in said container, said container and cover being made of non-conducting material, spaced electrodes carried by the cover and depending therefrom, an inner vessel of non-conducting heat insulating material surrounding the electrodes and having its upper end secured to said cover, said inner vessel being provided at the bottom with a relatively small opening, and said cover being provided with a relatively small central opening affording a steam outlet for the inner vessel.

3. A humidifier, comprising a water container, a movable cover closing a filling opening formed in said container, electrodes carried by the cover and extending downwardly therefrom, a depending collar formed integral with the cover and surrounding said electrodes, said inner vessel having its upper end open and engaging the lower edge of said collar, said inner vessel having a relatively small bottom opening and said cover having a relatively small central opening placing in the interior of the inner vessel in communication with the atmosphere and means for clamping the inner vessel to said collar.

4. A humidifier as recited in claim 3 including a gasket covering the joint formed between said collar and inner vessel and held in place by said clamping means.

5. A humidifier comprising an outer vessel, a cover closing a filling opening in the top of said vessel, an inner vessel depending from the cover in spaced relation to the bottom and side walls of the outer vessel, said outer vessel being adapted to contain a body of water surrounding the side and bottom walls of the inner vessel and said inner vessel,

- having its lower end closed except for a relatively small opening serving to admit therein a small quantity of water which is thereby segregated from the main body of water, and electrodes contained within the inner vessel for converting the segregate into steam, said cover being formed with a steam discharge opening placing the upper end of the inner vessel in communication with the atmosphere.
6. A humidifier comprising an outer vessel adapted to contain a body of water and provided with a top filling opening, a removable cover closing said opening, an inner vessel having its upper end releasably secured to the central portion of the cover so as to be supported in spaced relation to the bottom and side walls of the outer vessel, the lower portion of the inner vessel being apertured to admit therein a relatively small quantity of water which is thereby subsequently segregated from the main body of water contained in the outer vessel, and electrodes contained within the inner vessel for converting the segregate into steam, said cover being formed with a central steam discharge opening placing the upper end of the inner vessel in communication with the atmosphere.
7. A humidifier comprising an outer vessel adapted to contain a body of water and provided with a top filling opening, a removable cover closing said filling opening, a collar depending from the central portion of said cover, an inner vessel having its upper end secured to said collar and thereby supported in spaced relation to the side and bottom walls of the outer vessel, the lower portion of the inner vessel being apertured to admit therein a relatively small quantity of water which is thereby segregated from the main body of water contained in the outer vessel and electrodes contained within the inner vessel for converting the segregate into steam, said cover being formed with a central steam discharge opening placing the upper end of the inner vessel in communication with the atmosphere.
8. A humidifier comprising an outer vessel adapted to contain a body of water and provided with a top filling opening, a removable cover closing said filling opening, a pair of depending electrodes having their upper ends secured to said cover, an inner vessel surrounding said electrodes, the upper end of the inner vessel being releasably secured to said cover and the lower end of the inner vessel being apertured to admit therein a relatively small quantity of water which is thereby substantially segregated from the main body of water contained in the outer vessel, said cover being provided with a central steam discharge opening placing the upper end of the inner vessel in communication with the atmosphere.
9. A humidifier comprising an outer vessel adapted to contain a body of water and provided with a top filling opening, a removable cover closing said opening, the central portion of said cover being in the form of a hollow steam dome provided at the top with a steam discharge opening, a pair of spaced depending electrodes having their upper ends secured in the dome portion of the cover, an inner casing surrounding said electrodes, the upper end of said inner casing being releasably secured to said cover and the lower end being apertured to admit therein a relatively small quantity of water which is thereby substantially segregated from the main body of water contained in the outer vessel.
10. A humidifier comprising an outer vessel adapted to contain a body of water and provided with a top filling opening, a removable cover closing said opening, the central portion of said cover being in the form of a hollow steam dome provided at the top with a steam discharge opening, an inner vessel having its upper end releasably secured to said cover in communication with said steam dome, the lower end of said inner vessel being apertured to admit therein a relatively small quantity of water which is thereby substantially segregated from the main body of water contained in the outer vessel, and electrodes contained within the inner vessel for converting the segregate into steam which is discharged to the atmosphere via the opening formed in the top of the steam dome.
11. A humidifier comprising an outer vessel adapted to contain a body of water and provided with a top filling opening, a removable cover closing said opening, said cover being formed with a central steam discharge opening and with a depending collar surrounding said opening, an inner vessel having its upper end open and abutting the lower edge of said collar and having its lower end apertured to admit therein a relatively small quantity of water which is thereby substantially segregated from the main body of water contained in the outer vessel, an annular gasket surrounding the collar and the upper end of the inner vessel and closing the joint therebetween, a clamping member surrounding said gasket and serving to support the inner vessel, and electrodes contained within the inner vessel for converting the segregate into steam.
12. A humidifier comprising an outer vessel adapted to contain a body of water and provided with a top filling opening, a removable cover closing said opening, the central portion of said cover being shaped to provide an upwardly projecting hollow steam dome having a top steam discharge opening, terminal members projecting laterally through the side wall of said dome, depending electrodes having their upper ends received in the dome and secured to said terminal mem-

bers, and an inner vessel surrounding said electrodes, said inner vessel having its upper end open and releasably secured to the cover in communication with the steam dome and having its lower end apertured to admit therein a relatively small quantity of water which is thereby substantially segregated from the main body of water contained in the outer vessel in order to permit the segregate to be readily flashed into steam by supplying current to said electrodes, the steam thus generated being discharged to the atmosphere through the top opening of the steam dome.

15 In witness whereof, I have hereunto set my hand.
